A. E. LUNDELL

TELEPHONE SYSTEM

Filed Nov. 1, 1919

Inventor:

Alben E. Lundell

by *C. A. Soper Atty.*

UNITED STATES PATENT OFFICE.

ALBEN E. LUNDELL, OF CHICAGO, ILLINOIS, ASSIGNOR TO WESTERN ELECTRIC COMPANY, INCORPORATED, OF NEW YORK, N. Y., A CORPORATION OF NEW YORK.

TELEPHONE SYSTEM.

Application filed November 1, 1919. Serial No. 334,945.

To all whom it may concern:

Be it known that I, ALBEN E. LUNDELL, a citizen of the United States, residing at Chicago, in the county of Cook, State of Illinois, have invented certain new and useful Improvements in Telephone Systems, of which the following is a full, clear, concise, and exact description.

This invention relates to special service systems for telephone exchanges.

In the systems employing so-called manual working, that is, where operators are employed for answering calls and for establishing connections, certain special service features have been developed, especially in private branch exchange working. One of these features is that termed "night service." Heretofore, such service has been provided by wiring special apparatus into the cord circuits providing night service keys for changing the character of such circuits and keys for changing the character of other circuits in the switchboard. On the whole, such night service arrangements have been unsatisfactory, because only so many lines could be provided for as there were central office trunks, and then all calls between the lines had to be routed through the central office, thus transferring the duties of the private branch exchange operator to the central office operator.

The object of this invention is to provide a more flexible arrangement whereby such special service may be supplied to a larger number of subscribers and where the duty of switching will not be transferred from one operator to another, but will be performed automatically.

In accordance with this object, means are provided whereby the trunk lines and certain subscribers' lines may be provided with incoming service and this arrangement is not limited by any other arrangements at the exchange.

Also in accordance with this object, means are provided whereby certain subscribers' lines may be supplied with outgoing service to the central office or to any of the other subscribers' lines which are provided with the first-mentioned means.

Broadly, the first-mentioned means consists in a relay arrangement whereby the lines which may be called may have taps normally disconnected from the said lines

leading to the multiple banks of simple automatic switches.

Broadly, also, the second-mentioned means consists in a simple automatic switch which may be patched to a line to be temporarily provided with outgoing switches.

Hence, during the slack hours of the day or night, it is only necessary that the lines which are to have outgoing service be patched to an automatic switch whereupon the subscribers on those lines may, by simple manipulation of a substation dial switch, in accordance with modern automatic telephone practice, establish connection with the central office or any subscriber's line provided with incoming service arrangements.

Another object of the invention is to provide means whereby the potential on the testing points of a selective switch may be kept practically constant despite variations in the potential of the source of current.

In accordance with this object a relay sensitive to the change in potential of the source of current is provided which will act to raise the potential of the testing points when the first-mentioned potential is for any reason reduced below a certain level.

In the drawings, Figure 1 is a diagrammatical representation of the circuits employed in carrying out this invention. Figures 2 and 3 are schematic details of Figure 1 and are provided for the purpose of clearly explaining the operation of means for equalizing the potential of the testing points.

The drawing shows, in the upper right-hand corner, three lines, each terminating in a manual switchboard. The line 1 is an ordinary subscriber's line terminating in a jack 2. The subscriber at substation 1, by removing his receiver from the hook, may cause the lamp 3 to be lighted in a series circuit including the substation loop. The subscriber at substation 4 is provided with a jack 5 and may, in the same way, cause the illumination of signal lamp 6. It will be noted that the subscriber's loop to the substation 4 passes through the back contacts of a relay 7, but in every other respect this line is, under normal conditions, the same as that to substation 1. A line 8 terminates at a central office (not shown) and is there provided with the usual arrangements, that is, a line and cutoff relay, signal lamp, answering jack

and multiple jacks. The trunk line 8 terminates at the manual switchboard in a jack 9 associated with which is a lamp 10. The central office operator, by plugging into 5 a multiple jack at the central office and ringing over the line will energize the right-hand winding of relay 11 in a series circuit including the contacts of the jack 9 and the condenser 12. Relay 11, upon energizing, 10 closes a circuit from battery, the left-hand winding of the relay 11, the contact 13 on the jack 9, the armature and contact of relay 11, the lamp 10 to ground. Calls established to the manual switchboard may be 15 answered and connections established in the well-known manner.

In the upper part of the drawing, near the left-hand end is shown a cord circuit 14 provided at each end with a plug 15 and 20 16 respectively. This double ended cord is used for patching purposes, as will hereinafter be described.

The lower part of the drawing shows the circuits to an automatic switch having 25 brushes 17, 18, 19, 20, 21 and 22 associated with a terminal bank, numbered as a whole, 28. Each set of terminals in this bank may be connected with a trunk line, such as that numbered 8, leading to a central office, or a 30 subscriber's line such as 4, leading to a substation within the exchange. Each subscriber's line, such as 4, is provided with a relay 7 and a pair of taps which, under the influence of relay 7, may be connected to 35 the substation 4. Each trunk line, such as 8, is provided with a relay corresponding to 7, here numbered 24, which is instrumental in connecting the pair of taps from the multiple 23 to the trunk line 8.

40 Let it be assumed that the slack hour of the day has been reached and the operator wishes to leave the board and at the same time provide service for certain of the sub-subscribers who may have occasion to use 45 their telephones. Let it be further assumed that a subscriber at substation 1 will wish to use his telephone during such slack hours to establish connections to the central office over the trunk 8 and to a subscriber at 50 station 4. The operator thereupon inserts the plug 16 into the jack 2 and the plug 15 into the jack 25. No other arrangements need be made by the operator.

Let it be assumed that the subscriber at 55 substation 1 now wishes to communicate with the subscriber at substation 4. In removing his receiver from its hook, the subscriber at substation 1 will energize relay 26 through a circuit extending from battery, left-hand winding of relay 26, contact and outer left-hand armature of relay 27, line 28, relay 29, ring of the jack 25, ring of the plug 15, ring of the plug 16, ring of the jack 2 through the loop of the 60 substation 1, tip of the jack 2, tip of the plug 65

16, tip of the plug 15, tip of the jack 25, line 30, inner left-hand armature and contact of relay 27, right-hand winding of relay 26 to ground. Relay 26 alone energizes in this circuit and in so doing a circuit is established 70 from ground, brush 22, the contact upon which it normally rests, conductor 31, right-hand armature and contact of relay 27, armature and front contact of relay 26, winding of relay 32 to battery and ground. Relay 75 32 energizes in this circuit and through its left-hand armature establishes a circuit from ground, left-hand armature and contact of relay 32, winding of relay 33 to battery and ground. Relay 33, upon energizing, 80 connects the motor magnet 34 through the winding of relay 35 to the back contact of relay 26.

If the subscriber at substation 1 now manipulates his sender 36, the brushes of the switch 23 will be positioned on the set or terminals associated with the substation 4. Upon each interruption of the line circuit, the relay 26 will be deenergized and thereupon a circuit will be established from ground, brush 22, the contact upon which brush 22 normally rests, or after the brush 22 has left this contact from ground, the inner left-hand armature and contact of the relay 33 to the conductor 31, the right-hand 95 armature and contact of relay 27, the armature and back contact of relay 26, the winding of relay 35, the front contact and right-hand armature of relay 33, the winding of 100 motor magnet 34 to battery and ground. Six interruptions of the line circuit will cause this last traced circuit to be established six times and the motor magnet 34 to be energized six times whereupon the brushes 17 to 105 22 will be placed on the terminals leading to the substation 4.

Relay 35 serially included in the circuit with the motor magnet 34 being slow to release remains energized during the transmission of this series of impulses. During its 110 energization, a circuit is established from ground, the resistance 36, the front contact and armature of relay 35, the winding of relay 37 to battery and ground. Should the called substation 4 be idle, a connection will now be established from ground, the winding of relay 7, the contact upon which brush 21 now rests, brush 21, the outer left-hand armature and contact of relay 33, the contact and armature of relay 37, the winding of relay 37, to battery and ground whereupon the relay 37 is maintained energized and relay 7 becomes energized. After a short interval, the armature of relay 35 is retracted and a circuit is thereupon set up 115 from ground through the winding of relay 7, the outer left-hand armature and contact of relay 33, the contact and armature of relay 37, the armature and back contact of relay 35, both windings of relay 38 to bat- 120 125 130

tery and ground. Relay 38 becomes energized through its two windings in series. However, as soon as it attracts its armatures, its right-hand winding being shunted 5 through the agency of its inner right-hand armature and contact, the relay is held energized through its left-hand winding.

The condition of the testing circuit is now as illustrated in Figure 2, that is the left-10 hand winding of relay 38 and the winding of relay 37 are in multiple and through them current flows through the test brush 21 and the winding of relay 7 to ground.

It will be understood that circuits of the 15 nature of those shown in Figure 1 are used at points distant from a central office. In such cases the source of current is supplied over conductors from the central office and since there is more or less resistance in the 20 leads a heavy load at the switching point will reduce the potential of this source of current.

If the potential of the source of current is thus reduced, relay 37, being marginal, will 25 retract its armature and the condition shown in Figure 3 will be established. Here the right-hand winding of relay 38 will no longer be shortcircuited but will be included in a series circuit with the winding of relay 37, 30 whereupon the relative potential at the brush 21 will be raised due to the larger amount of resistance included between it and the source of current. This rise in potential will compensate for the drop in potential of the source of current and thus 35 the potential of the testing points will remain practically constant.

Relay 38, through its energization, connects the wires 39 and 40 to the wires 41 and 42 respectively leading to the brushes 17 and 18 respectively. At the same time, a circuit is established from ground, the contact and inner left-hand armature of relay 33, conductor 31, right-hand armature and 45 contact of relay 27, the armature and front contact of relay 26, conductor 43, the contact and outer right-hand armature of relay 38, brush 19, the terminal upon which it rests, conductor 44, contact and armature 50 of ringing relay 45, back contact and armature of relay 46, winding of relay 47 to battery and ground. Relay 47 in energizing, establishes a ringing circuit for calling the subscriber at substation 4. This circuit may 55 be traced from the source of ringing current 48 through the winding of relay 45, the front contact and outer armature of relay 47, the conductor 40, the outer left-hand armature and front contact of relay 38, conductor 42, brush 18, the terminal upon which it rests, the front contact and outer left-hand armature of relay 7 through the loop of the substation 4 and the signal dial thereat, the inner left-hand armature and front 60 contact of relay 7, the terminal upon which

brush 17 rests, brush 17, conductor 41, the front contact and inner left-hand armature of relay 38, conductor 39, inner armature and front contact of relay 47 to ground. The current flowing over this circuit from 70 the source of ringing current 48 is insufficient to energize the relay 45 until the subscriber at substation 4 removes his receiver from its hook. At this time, the relay 45 energizes, whereupon the circuit for the 75 energization of relay 47 is now changed to serially include the winding of relay 46. Relay 46, upon energizing, shunts the winding of relay 47 by the connection to battery at its front contact and right-hand armature 80 and is thereafter held locked in the circuit including brush 19, outer right-hand armature and contact of relay 38 to ground over the circuit heretofore described.

A conversational circuit between substation 1 and substation 4 is now established, and conversation may proceed, talking battery being furnished from the windings of 85 relay 26.

Let it be assumed that substation 4 was 90 already involved in a connection such as that just described. In this case, the test brush 21, upon being placed on the terminal connected to the winding of relay 7 would find not ground but a potential somewhat 95 between ground and battery and such potential would be insufficient to hold the relay 37 operated.

Hence, as soon as the armature of relay 35 was retracted from its front contact, relay 37 would become deenergized and there 100 would be no circuit for the energization of relay 38. In this case, a circuit from ground, the front contact and right-hand armature of relay 32 through the left-hand winding of impedance coil 49, the winding of buzzer magnet 50, the armature and back contact of buzzer magnet 50, the right-hand winding of impedance coil 49 to battery 105 would be established. Buzzer magnet 50 being provided with an armature and back contact in its own circuit would vibrate its armature and through rapid makes and breaks of the circuit just described would produce a tone which, transmitted over the back contact 110 and outer left-hand armature of relay 38 to condenser 51, the conductor 28, the outer left-hand armature of relay 27, the winding of relay 26 to battery and ground, 115 would produce, by induction, a tone in the receiver at the substation 1 thereby informing the subscriber at that substation that the called line 4 is busy.

The subscriber at substation 1 would 120 thereupon restore his receiver to its switchhook and through the opening of the loop to his substation, would deenergize relay 26. The armature of relay 26 upon contacting with its back contact establishes a circuit 125 previously described for the energization of 130

motor magnet 34, whereupon the brushes are stepped to the next set of contacts. In a short time, slow-releasing relay 32 becomes deenergized and in turn, relay 33 becomes deenergized whereupon a circuit is established from ground, the brush 22, the strip 52 upon which the brush 22 contacts in all positions except its normal position, this switch being of the rotary type, from the strip 52 through the armature and back contact and right-hand armature of relay 33, winding of magnet 34 to battery and ground. Magnet 34 being included now in the self-interrupting circuit moves the brushes step-by-step until they have returned to their normal position whereupon the switch and the circuits therefor are in the position shown in the drawings.

Restoration from an established connection is accomplished in the same manner.

Let it be assumed that the substation 4 is connected to a set of terminals which are more than ten steps from the normal position of the switch, say 15. In this case, the substation 4 might be called through the number 96. If the subscriber at substation 1 first dialled 9 he would set the brushes of the switch on the ninth set of terminals which would, under these conditions be blank, that is, no multiple wire would be connected to them. At the end of this series of nine impulses, the circuits of the switch would be as described when a busy line is reached, that is, relay 37 would become deenergized and prevent the energization of relay 38. Thereupon the subscriber would dial the digit 6 and the brushes would be advanced six more steps, that is, to the fifteenth set of terminals and to the line number 96, here shown as substation 4.

It will now be assumed that the subscriber at substation 1 wishes to establish connection to the central office over the trunk 8, as indicated on the drawings, but will dial 3, that is he will manipulate his sender 36 to transmit three impulses or rather to interrupt his line three times. In the manner heretofore described, the brushes 17 to 22 inclusive will be placed on the terminals leading to the trunk 8. If the trunk is busy, a performance heretofore described will be repeated and the busy tone being received by the calling subscriber, he will disconnect and his switch will be restored to normal position. If, on the other hand, the trunk to the central office is idle, the relay 38 will be energized, but since the brush 19 now rests on a terminal which is not connected to the conductor 44, the relay 47 will not be energized. Relay 24 having been energized in a circuit including the brush 21 and the left-hand winding of relay 38 will, through its winding and armatures connect a relay 53 to the lines leading to

the central office over the circuit including the high resistance line relay usually provided at the central office, but will, however, cause the line relay to be energized and the calling lamp illuminated. The operator at the central office, plugging into the trunk will, through her cord circuit, supply an increased potential whereby the relay 53 will be energized. Thereupon a circuit is established from ground, contact and armature of relay 53, the winding of relay 54 to battery and ground. Relay 54, in attracting its armatures, establishes a locking circuit for itself from ground, left-hand armature and contact of relay 24, the contact and inner right-hand armature of relay 54 to battery and ground. Also a circuit is established from ground, outer right-hand armature and contact of relay 54, terminal upon which brush 20 rests, winding of relay 27 to battery and ground. Relay 27, through its left-hand armatures cuts off the relay 26 from the connection and at its inner right-hand armature removes the ground from the armature of relay 26 whereby, when relay 26 retracts its armature, the motor magnet 34 will not be again energized. Relay 27 in attracting its outer left-hand armature connects conductor 28 to conductor 40. Relay 54 also through its left-hand armatures connects the trunk 8 to the terminals upon which brushes 17 and 18 rest and thereupon establishes a conversational circuit between the subscriber at substation 1 and the trunk 8, battery being supplied from the central office for talking purposes. This battery current flowing through the supervisory relay 29 energizes this relay to establish a circuit from ground, the contact and inner left-hand armature of relay 33, conductor 31, contact and armature of relay 29, the winding of relay 32 to battery and ground to hold relay 32 and consequently relay 33 energized during the establishment of this connection.

When the conversational period terminates and either the subscriber at substation 1 hangs up his receiver or the operator at the central office removes her plug from the trunk 8, the relay 29 will be deenergized whereupon relay 32 and in turn, relay 33 become deenergized. The motor magnet 34 is now included in a self-interrupting circuit and the switch will be restored to its normal position as heretofore described.

It will be seen from the foregoing description that night service may be supplied to any number of substations and central office trunks as may be required, the only limit being the capacity of the automatic switch. It will also be seen that outgoing night service may be supplied to as many subscribers as there are automatic switches. The only arrangements which the operator has to make upon leaving the board, are to

patch substations which are to receive outgoing service to the automatic switches through the agency of jacks, such as 25. A substation may have outgoing service and not incoming service. Again a substation 5 may have incoming service and not have outgoing service or it may have both. Incoming service over a trunk line from the central office may be arranged if the central 10 office operator is supplied with a sender in her cord circuit.

What is claimed is:

1. In a telephone system, lines and trunk lines, manual means for interconnecting said 15 lines and for interconnecting said lines and said trunk lines, automatic switches, multiple terminal banks for said automatic switches, means individual to certain of said lines and said trunk lines for connecting said lines and trunk lines to said multiple 20 terminal banks, means for connecting said switches to certain of said lines, and means responsive to said last lines for operating said switches to operate said individual 25 means and establish connections to said lines and said trunk lines.

2. In a telephone system, a manual switch-board, a plurality of automatic switches, lines terminating in said manual switch- 30 board, means for establishing connections

through said automatic switches to certain of said lines, said certain lines being normally disconnected from said switches and means for temporarily connecting certain of said lines each to one of said automatic 35 switches whereby said last lines may control said switches to establish connections to said first said certain of said lines.

3. In a telephone system, an automatic switch having a testing contact, a controlling circuit having therein a plurality of electromagnets and a source of current, one 40 of said electromagnets being sensitive to changes in the potential of said source of current and having means responsive thereto to alter the number of said electromagnets 45 to control the potential of said testing contact.

4. In a telephone system, an automatic switch having a testing contact, a controlling circuit having therein a plurality of electromagnets and a source of current, one 50 of said electromagnets being sensitive to changes in the potential of said source of current and having means to control the 55 potential of said testing contact.

In witness whereof, I hereunto subscribe my name this twenty-eighth day of October A. D., 1919.

ALBEN E. LUNDELL.
